UNITED STATES PATENT OFFICE

2,516,572

SOLDERLESS TYPE TERMINAL

Herbert E. Heller, West Allis, Wis., assignor to
 Cutler-Hammer, Inc., Milwaukee, Wis., a corporation of Delaware

Application October 31, 1947, Serial No. 783,331

4 Claims. (CL 173—269)

1

This invention relates to improvements in solderless type terminals and methods of making the same.

With respect to terminals of the aforementioned character there are a number of important requirements, certain or all of which have not been met by the solderless type terminals now on the market. Among those requirements may be mentioned: (1) A sufficient length of rigidly supported screw thread must be available to prevent stripping thereof by the thread on the clamping screw upon tightening of the latter; (2) the stationary member of the terminal clamp must be stiff enough to withstand the torque which is applied when the screw is tightened against the wire; (3) the wire-receiving space must be narrow, and of substantially the same width as the diameter of the clamping screw, so as to properly confine the wire during and after the clamping operation; and (4) the construction must be such as to minimize the cost of material and labor for production of the finished article.

An object of the invention is to provide a solderless type terminal having all of the aforementioned desirable features.

Another object is to so construct and arrange the parts of the terminal as to provide for use thereof where a limited space is available, particularly in respect of the permissible width of the terminal.

Another object is to provide a terminal of the aforementioned character having suitable means to afford a separate additional electrical connection.

Another object is to provide a novel method of assembling the parts of such a terminal and novel means for retaining said parts in assembled relation.

Another object is to provide novel means for removably attaching a stationary contact member to the terminal, after attachment of the latter to a suitable support.

Another object is to simplify the construction of and the manner of assembling the parts of terminals of the aforementioned character.

Another and more specific object is to minimize the required thickness of the nut blank employed while affording the desired length of thread to be engaged by the clamping screw.

Other objects and advantages of the invention will hereinafter appear.

The accompanying drawings illustrate certain embodiments of the invention, which will now be described; it being understood that the embodiments illustrated are susceptible of modification

2

in respect of certain structural details thereof without departing from the scope of the appended claims.

In the drawings,

5 Fig. 1 illustrates (in double scale) one form of my improved solderless terminal, and the manner in which the same may be permanently attached to an insulating base of suitable form; a stationary switch contact being shown removably attached to the terminal.

Fig. 2 is an outer end view of the terminal shown in Fig. 1; the auxiliary wiring terminal screw being omitted to better illustrate the structure.

15 Fig. 3 is a top plan view of the terminal shown in Fig. 2, but with both the main terminal clamping screw and the auxiliary wiring terminal screw omitted.

Fig. 4 is a top plan view of the current carrying part of the terminal.

20 Fig. 5 is an end elevational view of the punched and stamped sheet metal yoke member prior to assembly and attachment of the nut and the current carrying part thereto.

25 Fig. 6 is an outer end view of a modified form of terminal, wherein a previously drilled and tapped nut and the conducting member are assembled with respect to a yoke member, consisting of a tube section, by distortion or inward bending of the side walls of the latter; the screw when assembled with respect to the nut acting to positively prevent separation of the latter from the yoke.

30 Fig. 7 is a side elevational view of the device shown in Fig. 6; only a fragment of the conducting member being illustrated.

Fig. 8 is an end view, partly in elevation and partly in section, of a further modified form of terminal, wherein a relatively thinner nut blank

40 is rigidly united with a tubular yoke, preparatory to drilling and tapping of said parts jointly to accommodate the shank of the clamping screw.

Fig. 9 is a view similar to Fig. 8, showing in dotted lines the manner in which the upper end wall of the yoke and the nut blank may be drilled and tapped after uniting of said parts, and

Fig. 10 is a side elevational view of the device shown in Figs. 8 and 9; only a fragment of the conducting member being illustrated.

45 Referring to Figs. 1 to 5 of the drawings, the numeral 10 designates a substantially U-shaped yoke, which is initially formed as shown in Fig. 5 from a punched and stamped blank of sheet metal. I prefer to employ for yoke 10 a metal, such as cold rolled steel, which is of great strength

and toughness; it being understood by those skilled in this art that there is no necessity for yoke 10 to be of unusually good electrically conducting character. The bottom wall or connecting portion 11 of yoke 10 is of predetermined width (as shown in Fig. 1), and portions 12 and 13 of the upstanding arms thereof are of a width corresponding thereto; said portions 12 and 13 being integrally connected with the relatively wider upper end portions 14 and 15 through the medium of the gradually widening portions 16 and 17.

In the initial form of yoke 10, as shown in Fig. 5, the arm portions 14 and 15 are provided with outward offsets, through the medium of the bends 18 and 19, respectively. The outwardly angled upper end portions of said arms are preferably each provided with a pair of inwardly extruded bosses; one boss of each pair being shown in Fig. 5, and respectively designated by numerals 20 and 21; said bosses being adapted to facilitate a spot-welding operation, as hereinafter described. The external depressions required to form bosses 20 and 21 are designated by numerals 20^a and 21^a. The extreme upper ends of said arm portions 14 and 15 are bent inwardly at an angle, as shown at 22 and 23.

The conducting member of the terminal preferably consists of a strip of brass 24, of the shape and relative size illustrated in Figs. 1 to 4. Member 24 is preferably notched, when in flat or blank form, as indicated at 25 and 26 in Fig. 4, to provide a relatively narrower or neck portion 27, the width of which preferably closely corresponds with the length of the aforementioned connecting portion 11 of yoke 10.

The brass member 24 is provided with a flat rear end portion 28 having a circular opening 29 formed therein, for a purpose to be described; an integral upwardly offset portion 30 having a tapped opening 31 formed therein, for a purpose to be described; and the forward end portion of member 24 is further bent to extend upwardly, then forwardly flatwise, and then downwardly, as indicated by the portions 32, 33 and 34 in Fig. 1, to a sort of inverted U-shape. As best illustrated in Figs. 2 and 4, the upper surface of the flat portion 33 is provided with a pair of transversely extending raised or extruded portions 35 and 36, in a predetermined spaced relationship to each other, and each comprising alternate grooves and ridges extending longitudinally of flat portion 27, as best illustrated in Fig. 2. As an incident to the bends between portions 32 and 33 and portions 33 and 34, the lower ends of the spaced shoulders 37, 38 and 39, 40 are angled inwardly toward each other to afford a spacing thereof only slightly greater than the width of the portions 12 and 13 of the arms of yoke 10.

In assembling the parts of the terminal, the conducting member may be inserted downwardly into yoke 10 (Fig. 5) in a manner to provide for accommodation of the arm portions 12 and 13 within notches 25 and 26. Thereafter a rectangular steel block 41, preferably of square peripheral contour, is freely insertable, either downwardly or laterally, between the portions 14 and 15 of the yoke arms; said block being adapted to rest temporarily upon the inner surfaces of the aforementioned bends 18 and 19. The arms of the yoke 10 are then pressed inwardly toward each other, until the inner ends of the bosses 20 and 21 engage one pair of opposite parallel sides of block 41; the pressure upon said arms being

maintained during application of a suitable welding current, which results in fusion of the bosses 20 and 21 to effect spot-welding of said arms to block 41, as indicated by the relative positions of the yoke arms in Fig. 2. The extreme upper ends 22 and 23 of the arms of yoke 10 will then overlap to some extent the upper surface of block 41.

Thereafter the relatively narrow portions 12 and 13 are bent inwardly at the points 42 and 43 (Fig. 2) to overlie a portion of the upper surface of the reduced or neck portion 27 of the current carrying member 24, to rigidly and permanently secure the latter and yoke 10 in fixed relationship to each other.

A screw or bolt 44, preferably having a kerfed head as shown, has its shank 44^a in threaded engagement with a tapped opening 41^a formed in the block 41. In practice I prefer to provide block 41 with a drilled and tapped opening after said parts are united by welding, as aforescribed. As best illustrated in Fig. 2, the diameter of screw shank 44^a is only slightly less than the distance between the portions of the yoke arms extending from the lower surface of nut 41 to the upper surface of member 24, to insure proper clamping of a conductor (not shown) between the lower end of screw shank 44^a and member 24. I prefer to provide screw 44 with a convex lower end 44^b, although said screw end may be made flat, conical, or of other shape if desired.

As will be apparent from consideration of Figs. 1 and 2, the screw, when tightened against an inserted wire or conductor, will cause the conductor to be bent or distorted between the spaced portions 35 and 36 on member 24, and the wire will be pressed into the desired degree of interlocking engagement with member 24 to insure against accidental displacement or loosening of the wire.

While I have shown the screw 44 as of the kerfed type, to provide for operation thereof by a screw driver, it will be understood that the head thereof may be of polygonal contour (as illustrated) to provide for alternative operation thereof by a wrench of any suitable or well-known form.

The downwardly bent outer end portion 34 of member 24 is preferably provided with a tapped opening 34^a to accommodate the threaded shank 45^a of a screw or bolt the hexagonal head of which is shown at 45 in Fig. 1, to provide for operation thereof by a wrench. As shown, the head 45 may also be provided with a kerf to permit operation of said screw by means of a screw driver. The circuit wire or wires (not shown) may be clamped to the outer surface of portion 34 in the usual manner, a flat washer 46 and a lock washer 47 being preferably interposed between the conductor and the screw head 45.

As shown in Fig. 1, the assembled terminal parts thus far described are adapted to be positioned within a groove 48^a of rectangular form in transverse cross section, and of only slightly greater width than member 24, formed upon the upper surface of an insulating base, a fragment of which is shown at 48. Base 48 is preferably provided with an opening or passage 48^b to accommodate the tubular shank of a headed rivet 50 which passes downwardly through the aforementioned opening 29 in member 24 and through a suitable metal washer 51, and is upset over the lower surface of the latter, as indicated at 50^a.

After rigid and permanent attachment of the solderless terminal to base 48 as just described, a stationary switch contact assembly (compris-

ing a punched plate 52 of metal of good electrical conductivity, such as copper, brass or bronze, and having a contact tip 53 of silver or a silver base material rigidly and permanently attached thereto) is removably attached to the solderless terminal, as by means of a screw 54 whose threaded shank penetrates a clearance opening provided in plate 52 and takes into the aforementioned tapped opening 31 (Figs. 3 and 4) in member 24; a split lock washer 55 being preferably interposed between the head of screw 54 and the plate 52. Base 48 is shown as recessed at 48^c and 48^d to accommodate the shanks of screws 54 and 45.

As will be apparent from consideration of Fig. 2, the extreme upper end portions 22 and 23 of the arms of yoke 10 might be bent or wiped inwardly over the upper surface of nut 41, after the aforementioned spot-welding operation, if considered desirable for any reason, such as improving the appearance of the device.

At 56 in Fig. 1 I have shown one end of a movable or bridging contactor having a contact tip 57 thereon for cooperation with the aforementioned contact tip 53.

As best illustrated in Fig. 1, the lower surface of member 24 is pressed upwardly, as shown in dotted lines at 35^a and 36^a, as an incident to formation of the aforementioned raised or extruded portions 35 and 36. Although I prefer to form the member 24 of brass, it is to be understood that said member might be composed of another metal of good electrical conductivity, such as copper or bronze.

Also, as shown in Fig. 1, the flat bottom wall of recess 48^d is of sufficient width to accommodate and afford a seat for the straight lower edge 34^b of portion 34 of conducting member 24. The seating of edge 34^b against the aforementioned portion of base 48 assists in preventing distortion or displacement of any portion of conducting member 24 as an incident to tightening of the aforementioned terminal screw 45. As will be understood, in a given switch mechanism the number of screws 45 employed will ordinarily depend upon the number of solderless connectors required; said screws 45 affording the internal connections for the switch parts.

In the modified form of solderless, or clamp type, terminal shown in Figs. 6 and 7 certain of the parts may be identical with those shown in Figs. 1 to 5, and the same have been given corresponding numerals of reference. Thus, in Figs. 6 and 7, the screw 44 and metal conductor member 24 may be identical with the corresponding parts aforescribed. However, the yoke member 58 in this form of my invention is shown as consisting of a section or length of cold rolled steel tubing (preferably seamless). The upper end portion of yoke 58 may be initially formed with the flat upper end wall 58^a, the straight side wall portions 58^b and 58^c, and the inwardly bent or offset portions 58^d and 58^e, which form shoulders to prevent downward displacement of a nut 41^x (which preferably corresponds in shape and size with the block 41 of Fig. 2, but is provided with a drilled and tapped opening 41^y prior to assembly thereof with respect to yoke 58). Thus, the nut 41^x may be inserted or slid laterally into the upper end portion of yoke 58, the upper end wall 58^a of which is provided with a circular opening 58^f of only slightly greater diameter than the diameter of the shank of screw 44. Upon threading of screw 44 into the tapped opening 41^y in nut 41^x the peripheral wall of opening 41^y

will cooperate with said screw shank to prevent any substantial degree of lateral displacement of nut 41^x with respect to yoke 58.

The metal conductor member 24 of Figs. 6 and 7 is inserted within yoke 58 and seated against the lower end wall of the latter, whereupon the lower end portions of the side walls of said yoke are pressed, rolled or otherwise offset inwardly, as shown at 58^g and 58^h, to overlie and engage the upper surface of member 24, the side edges of which are notched as aforescribed, whereby member 24 and yoke 58 are rigidly and permanently united.

If desired, the upper end portion of yoke 58 may be spot welded to nut 41^x, in Figs. 6 and 7; although for practical purposes such permanent attachment of these parts in this form of my invention is not necessary; elimination of such spot welding operation effecting a substantial saving in the cost of assembly of said parts.

In the further modified form of my invention shown in Figs. 8, 9 and 10 the clamping screw 44 may be identical with the corresponding part in the other figures aforescribed; although, if desired, the screw employed in Figs. 8, 9 and 10 might be shortened to a degree corresponding to the thickness of the upper end wall 59^a of the yoke 59, thus correspondingly reducing the overall height of the complete unit. The yoke 59 (like the yoke 58 of Figs. 6 and 7) preferably consists of a suitable length of cold rolled seamless steel tubing; the length of said section preferably corresponding to the length of the respective sides of the square steel block 60 here employed. Block 60, as shown, is substantially thinner than the block 41 (Fig. 2) or the nut 41^x (Fig. 6), and is rigidly and permanently attached to the upper end wall 59^a of yoke 59, as by spot welding at a plurality of points, as indicated at 59^b and 59^c in Fig. 9. After uniting block 60 to yoke 59 the upper end wall 59^a and block 60 are provided with a drilled and tapped opening common thereto, as indicated by the inner and outer pairs of dotted lines 61 and 62 in Fig. 9. In this manner a thread of sufficient length and strength is provided for cooperative engagement by the threaded shank of screw 44.

The punched and stamped metal member 63 of good electrical conductivity is substantially like the member 24 aforescribed, but differs therefrom only in respect of the increased length of the slots on opposite sides thereof (one of which is shown in dotted lines at 64 in Fig. 10) to accommodate the length of the tube section forming the yoke 59. Member 63 is inserted into yoke 59 and seated against the lower end wall thereof, whereupon the side walls 59^d and 59^e are bent or pressed inwardly at 59^f and 59^g to overlie and engage the upper surface of member 63, whereby the latter is rigidly and permanently attached to yoke 59, as aforescribed. The other portions of member 63 may be of the same shape and size as the corresponding portions of the aforescribed member 24.

As shown in Figs. 8 and 9 the side walls of yoke 59 may be bent or pressed inwardly at 59^h and 59ⁱ either before or after insertion of block 60 into or permanent attachment thereof to yoke 59 by spot welding as aforescribed; thus not only rigidifying yoke 59, but also insuring formation of a conductor wire receiving opening in yoke 59 which is only slightly greater than the diameter of the shank of screw 44, for the purpose aforespecified.

I claim:

1. A solderless type terminal clamp comprising a U-shaped sheet metal yoke, a metal conductor member positioned within said yoke at the lower end thereof, and a nut and bolt carried between the upstanding arms of said yoke, said nut forming the upper wall of said clamp, and said upstanding arms of said yoke being deformed about said conductor member and said nut to afford retention of said parts in assembled relation and simultaneously to afford spacing of said arms just sufficient to provide clearance therebetween for said bolt when threaded downwardly to effect clamping of a conductor wire between said bolt and said conductor member.

2. A solderless type terminal clamp comprising a U-shaped metal yoke, a metal conductor member positioned within said yoke at the lower end thereof and having an interlocking engagement with the upstanding arms of said yoke, a nut carried between said arms and forming the upper wall of said clamp, a bolt threaded into said nut, the intermediate portions of said arms being bent inwardly to overlie said conductor and to underlie said nut to retain those parts in assembled relation and simultaneously to afford spacing of said arms just sufficient to provide clearance therebetween for said bolt when threaded downwardly to effect clamping of a conductor wire between said bolt and said conductor member, and the upper ends of said arms being bent inwardly to prevent upward displacement of said nut.

3. A solderless type terminal clamp comprising a U-shaped metal yoke, a metal conductor member positioned within said yoke at the lower end thereof, said conductor member having rectangular notches formed in opposite side edges thereof to interlock with the upstanding arms of said yoke, a nut carried between said arms and spot welded thereto, said nut forming the upper wall of said clamp and having a bolt threaded therethrough, the intermediate portions of said arms being bent inwardly to overlie said conductor member and to underlie said nut to retain those parts in spaced relation and simultaneously affording spacing of said arms just sufficient to

provide clearance for said bolt when threaded downwardly to effect clamping of a conductor wire between said bolt and said conductor member.

4. A solderless type terminal clamp comprising a U-shaped metal yoke, a metal conductor member positioned within said yoke at the lower end thereof, said conductor member having rectangular notches formed in opposite side edges thereof to interlock with the upstanding arms of said yoke, a nut carried between said arms and spot welded thereto, said nut forming the upper wall of said clamp and having a bolt threaded therethrough, the intermediate portions of said arms being bent inwardly to overlie said conductor member and to underlie said nut to retain those parts in spaced relation and simultaneously affording spacing of said arms just sufficient to provide clearance for said bolt when threaded downwardly to effect clamping of a conductor wire against said conductor member, the latter having transverse ridges to aid in clamping said wire securely and additionally having a downwardly bent portion having a screw threaded therethrough for attachment of additional circuit wires.
